UNITED STATES PATENT OFFICE.

MICHAEL J. BERNHARD, OF BUFFALO, NEW YORK.

DESIGN FOR A SIDEBOARD OR SIMILAR ARTICLE OF FURNITURE.

45,516.

Specification for Design.

Patented Mar. 31, 1914.

Application filed January 30, 1914. Serial No. 815,557. Term of patent 14 years.

To all whom it may concern:

Be it known that I, MICHAEL J. BERNHARD, a citizen of the United States, residing at Buffalo, in the county of Erie and State of New York, have invented a new, original, and ornamental Design for Sideboards or Similar Articles of Furniture, of which the following is a specification.

The accompanying drawing is a perspective view of a sideboard showing the design.

I claim:

The ornamental design for a sideboard or similar article of furniture, as shown.

MICHAEL J. BERNHARD.

Witnesses:

RAY A. MALTBY,
LOUIS BISCHOFF.
